US00D898216S

(12) **United States Design Patent** (10) Patent No.: **US D898,216 S**
(45) Date of Patent: ** Oct. 6, 2020

(54) **DEVICE FOR PERFORMING ELECTRICAL MEASUREMENTS**

(71) Applicant: **Mimetas B.V.**, CH Leiden (NL)

(72) Inventors: **Arnaud Nicolas**, Leiden (NL);
Frederik Schavemaker, Leiden (NL);
Sebastiaan Johannes Trietsch, Leiden (NL)

(**) Term: **15 Years**

(21) Appl. No.: **35/507,516**

(22) Filed: **May 15, 2019**

(80) **Hague Agreement Data**

Int. Filing Date: **May 15, 2019**

Int. Reg. No.: **DM/203358**

Int. Reg. Date: **May 15, 2019**

Int. Reg. Pub. Date: **Oct. 18, 2019**

(51) LOC (12) Cl. **24-02**

(52) U.S. Cl.

USPC **D24/216**

(58) **Field of Classification Search**

USPC D10/75, 78, 81; D24/107, 216, 223-234

CPC G01N 2201/022-0228

See application file for complete search history.

(57) **CLAIM**

The ornamental design for device for performing electrical measurements, as shown and described.

DESCRIPTION

1. Device for performing electrical measurements

1.1 : Perspective

1.2 : Top

1.3 : Bottom

1.4 : Rear

1.5 : Front

1.6 : Side

1.7 : Side
